UNITED STATES PATENT OFFICE

CHARLES H. TEGMEYER, OF ST. LOUIS, MISSOURI

BOAT DRIVE

Application filed April 20, 1928. Serial No. 271,464.

This invention relates broadly to boat drives, and more particularly to an improved mechanism for actuating the propelling means of a boat. It relates still more particularly to a driving mechanism for a boat having a propeller shaft adapted to be driven from more than one point, such as at or near its opposite ends, the propeller lying between the driven points on the shaft. An example of this type of drive is to be found in the common stern wheel boat such as is used in river navigation.

In driving the propeller or paddle wheel of a boat of the type above mentioned, it is important that equal forces be applied at all times to the respective driving points on the propeller or paddle wheel shaft. If the torque exerted on the shaft is greater at one of the driving points than at the other, unequal stresses are set up which not only tend to weaken the shaft but also greatly reduce the efficiency of the drive. It is also desirable in this type of drive to provide for operation of the propeller shaft at varying speeds and to insure equal driving forces at the two driving points on the shaft at any speed.

I provide a boat drive comprising a main or primary driving means to which are operatively connected subsidiary driving means, each of which subsidiary driving means is in turn connected with the propelling means through a slip connection or clutch. The main driving means is so disposed with relation to the subsidiary driving means that the forces exerted on the former by the latter substantially counterbalance each other, at least in one direction, whereby a smooth operation is attained and the wear on the driving parts is small.

I further provide, in a boat drive of the type mentioned, an idling unit comprising essentially the primary driving means and at least a portion of the subsidiary driving means, the primary driving means being substantially counter-balanced as above described, such idling unit being adapted for continuous operation whether or not the boat is being propelled. The slip connections or clutches above mentioned serve as means

whereby the idling unit may at the will of the pilot be operatively connected to the propelling means to drive the same.

I also provide a control means whereby the respective clutches are at all times equally engaged in order to insure equal driving forces at the respective driving points on the propelling means. The idling unit, which may comprise a driving shaft and a plurality of auxiliary shafts, is preferably positively intergeared so as to insure operation of all parts of the idling unit upon rotation of the driving shaft. This provision minimizes wear and tear due to repeated starting and stopping of the driving shaft with the consequent saving in power necessary for starting the driving shaft from rest each time it has stopped. It also enables a more certain and facile control of the boat and renders it capable of easy maneuvering.

The respective clutches between the idling unit and the propelling means are preferably mechanically connected to a common control means whereby upon operation of the control means the respective clutches are operated simultaneously to the same extent. With the idling unit operating at a predetermined speed, the control means may be operated to engage the clutches to a desired extent, their cooperating friction surfaces slipping so as to effect operation of the propelling means at a speed less than that of the idling unit. Adjustment of the control means increases or decreases the speed of the propelling means as desired, the speed of the idling unit remaining generally constant, although it will, of course, vary to some extent due to variation in the load carried by it through the clutch connections.

I therefore provide a boat drive comprising a counterbalanced idling unit adapted to be continuously operated whether or not the boat is being propelled, and means for connecting a propelling means to the idling unit so as to cause operation of the propelling means at any desired speed, the connections between the idling unit and the propelling means being controlled to exert substantially equal forces upon the propell-

ling means at all times regardless of the speed of the latter.

In the accompanying drawings I have illustrated a present preferred embodiment of the invention wherein

5 Figure 1 is a top plan view of a boat drive with portions cut away;

Figure 2 is a vertical cross-section on the line II—II of Figure 1;

10 Figure 3 is a horizontal cross-sectional view through a portion of the drive;

Figure 4 is a detail of a portion of the control mechanism;

15 Figure 5 is a cross-section taken on the line V—V of Figure 4;

Figure 6 is a detail of a bearing ring; and

Figure 7 is a detail of a portion of the clutch mechanism.

Referring more particularly to the drawings, reference numeral 2 designates a driving shaft suitably connected to a source of power, not shown. The shaft 2 is mounted in journals 3. Keyed to the shaft 2 are oppositely disposed bevel pinions 4. The journals 3 are connected to a main frame 5 in which frame are journalled auxiliary shafts 6. The shafts 6 are disposed in substantially the same horizontal plane but are offset from one another with respect to a vertical plane 30 for a purpose to be presently described. The center lines of the shaft 2 and the shafts 6 all lie substantially in the same horizontal plane.

Keyed to one end of each of the shafts 6 35 is a bevel gear 7. One of these bevel gears meshes with one of the bevel pinions 4 and the other with the other bevel pinion. Rotation of the shaft 2 therefore causes, through the pinions 4 and gears 7, simultaneous rotation of the respective shafts 6 at the same speed and in the same direction. The components, in the direction of the axis of the shaft 2, of the forces exerted on such shaft by the bevel gears 7 are substantially 45 equal and opposite in direction, whereby the shaft 2 is substantially counterbalanced in its axial direction. It is therefore only necessary to journal it to provide for rotation, end thrust bearings not being required, 50 but if desired, such thrust bearings may be provided.

Encasing the pinions 4 and gears 7 is a supplemental frame 8 which is provided with bearing portions 9 for the shafts 6. 55 The supplemental frame 8 is also provided with slightly upstanding bearing portions 10 with which and with the rear portions of the gears 7 suitable floating bearing rings 11 cooperate. These bearing rings are provided with centrally disposed apertures 12 through which the shafts 6 are adapted to pass and have journalled therein tapered roller bearings 12^a which contact with the bearing portions 10 of the supplemental frame 8 and with the rear portions of the

respective gears 7. The supplemental frame 8 being permanently positioned with respect to the main frame 5, all end thrust of the shafts 6 and the gears 7 is taken up in the bearing rings 11. These rings rotate freely 70 between the gears 7 and the bearing portions 10 and maintain the gears positively in mesh at all times. Thus the driving shaft 2 is counterbalanced by the auxiliary shaft 6, and the latter are in turn in effect counterbalanced against each other by the bearing rings 11. Rotation of the shaft 2, therefore, 75 always causes positive and accurate rotation of the shafts 6, lost motion and gear wear being to a great extent eliminated by 80 the arrangement described.

Keyed to each of the shafts 6 is a circular clutch member 6^a having a clutch surface 6^b at its periphery. Suitably journalled in the main frame 5 and coaxial with the respective shafts 6 are shafts 13. Positively keyed at one end of each shaft 13 is a collar 14 having integral outstanding members 15.

Slidably mounted on each shaft 13 is a second collar 16 provided with upwardly extending bearing members 17. Pivoted to each of the bearing members 17 is an adjustable link 18, the opposite end of which is pivoted to a clutch member 19 which is itself in turn pivoted to one of the members 15, as 95 at 20, to rotate into and out of clutching engagement with circular clutch member 6^a.

Each of the collars 16 is provided with an annular recess 21 into which fits a jointed ring 22 composed of two semi-annular members connected together by bolts 23. Each of the members of the ring 22 is provided with an upstanding post 24 for a purpose to be presently described.

Pivoted in the frame 5 substantially below the annular recess 21 in each sleeve 16, as at 25, is a clutch lever 26 formed of strip material, as clearly shown in Figure 4, so as to be hollow. Opposite portions of the clutch lever 26 are provided with apertures 27 for reception of the posts 24 of the ring 22.

Pivoted at 28 in the frame is an operating lever 29 to which at points equidistant above and below the pivot 28, as at 30 and 31, respectively, are pivoted links 32, which links are in turn at their opposite ends pivoted to the upper ends of the respective clutch levers 26, as at 33. A control rope or other means 34 may be attached to the upper end of the lever 29 whereby operation of the lever may be effected from a remote point.

The driving shaft 2, together with the shafts 6 and the circular clutch members 6^a, form an idling unit adapted to continuously rotate regardless of whether or not the boat is being propelled. With the parts in the position shown in Figure 2, the clutch members 19 are in positive engagement with the clutch members 6^a, whereby the shafts 130

13 are caused to rotate with and at the same speed as the shafts 6. Movement of the control lever 29 in a clockwise direction, viewing Figure 2, causes the collars 16 through the agency of the links 32, clutch levers 26 and rings 22 to be moved outwardly on their respective shafts 13, thereby rocking the clutch members 19 about their pivots 20 through the agency of the adjustable links 18, and disengaging the clutches whereby the shafts 13 are permitted to come to a stop. The lever 29, links 32, clutch levers 26, sleeves 16 and links 18, are so adjusted that at all times, irrespective of the relative positions of the clutch members, both of the clutches are engaged to the same extent,—that is, with the same clutching force. By suitable manipulation of the control lever 29 the frictional engagement of the clutches may be adjusted at the will of the pilot so that the shafts 13 may either be caused to rotate at the same speed as the shafts 6 or at a desired speed less than that of the shafts 6. The speed of rotation of the shafts 13 is therefore dependent upon the pull exerted by the pilot upon the control rope 34.

Keyed to each shaft 13 adjacent its outer end is a sprocket 35. Suitably mounted in the boat in journals, not shown, is a propeller shaft 36 carrying intermediate its ends a propeller 37. This propeller, as shown, is of the paddle wheel type used on stern drive boats, as above described. Keyed adjacent each end of the propeller shaft 36 is a sprocket 38. Positively connecting the respective sprockets 35 and 38 at each end is a driving chain 39, whereby the rotation of the shafts 13 is imparted to the propeller shaft 36, the driving force at each end of the latter being substantially the same. Thus the speed of rotation of the propeller is easily and positively determined by the pull exerted by the pilot upon the control rope 34. The idling unit operates continuously, the points of operative connection between it and the propeller being at the respective clutches. In this arrangement the only parts subjected to any considerable wear are the clutch members 19 which, as shown, are of heavy construction to permit of their continued use under wear. As the clutch members wear down, the wear is compensated for by adjustment of the adjustable links 18 so that the drive may at all times be maintained in such adjustment that the desired equal driving forces will be imparted to the propeller 36 at its opposite ends.

Thus an improved boat drive, the parts of which are substantially counterbalanced and subjected to a minimum of wear, and which is adapted to be very easily controlled to effect a desired speed of the propeller, is provided. Provision is therefore made for

maneuvering the boat with great facility and at a high degree of efficiency.

While I have shown and described a present preferred embodiment of the invention, it is to be understood that the same is not limited thereto but may be otherwise embodied within the scope of the following claims.

I claim:

1. A boat drive comprising a driving shaft, driven shafts extending in different directions from the driving shaft and positively geared thereto, propelling means, and clutch connections between each of the driven shafts and the propelling means. 75

2. In a boat drive, a main shaft and lateral shafts positively geared together and operating as a unit, propelling means, and clutch connections between each of the lateral shafts and the propelling means. 80

3. In a boat drive, an idling unit comprising a main shaft and subsidiary shafts geared thereto, such idling unit being adapted to operate continuously whether or not the boat is being propelled, propelling means, clutch connections between each of the subsidiary shafts and the propelling means, and means for simultaneously operating the respective clutch connections, such connections being at all times equally engaged. 90

4. In a boat drive, a main shaft, counter-balancing shafts extending in different directions from the main shaft, geared thereto, and exerting thrusts thereagainst substantially in opposite directions, propelling means, and clutch connections between each of the counterbalancing shafts and the propelling means. 100

5. In a boat drive, a driving shaft, a plurality of opposed shafts operatively connected with the driving shaft and exerting thrusts there against a component of the resultant of which in the direction of the axis of the driving shaft is substantially zero, propelling means, and clutch connections between each of the second mentioned shafts and the propelling means. 110

6. In a boat drive, a driving shaft, shafts operatively connected with the driving shaft and substantially counterbalancing it in the direction of its axis, each of the second mentioned shafts being substantially counterbalanced between the driving shaft and thrust means disposed oppositely thereto, propelling means, and clutch connections between each of the second mentioned shafts and the propelling means. 115

7. In a boat drive, a driving shaft, shafts operatively connected with the driving shaft and substantially counterbalanced between the driving shaft and thrust means disposed oppositely thereto, propelling means, and clutch connections between each of the sec- 125

ond mentioned shafts and the propelling means.

8. In a boat drive, a plurality of inter-geared shafts, propelling means, clutch connections between each of the shafts and the

9. In a boat drive, a plurality of inter-geared shafts forming an idling unit adapted for continuous operation whether or not the boat is being propelled, propelling means, at least some of the shafts having clutch connections with the propelling

10. In a boat drive, a plurality of inter-geared shafts forming an idling unit adapted for continuous operation whether or not the boat is being propelled, propelling means, at least some of the shafts having clutch connections with the propelling means, and a single control for the clutch connections, the clutch connections of said latter mentioned shafts being at all times equally engaged.

11. In a boat drive, a plurality of operatively connected shafts, a single propelling means, clutch connections between each of the shafts and the propelling means, and control means for the clutch connections adapted to cause all the clutch connections to at all times be equally engaged.

12. In a boat drive, a plurality of operatively connected shafts forming an idling unit adapted for continuous operation whether or not the boat is being propelled, propelling means, clutch connections between each of the shafts and the propelling means, and control means controlling the clutch connections and adapted for connecting the idling unit with the propelling means so that all the clutch connections are at all times equally engaged.

13. In a boat drive, a counterbalanced idling unit comprising a plurality of shafts, propelling means, clutch connections between the respective shafts and the propelling means, and control means for engaging all the clutch connections equally at all times whereby the propelling means may be operated at a desired speed relative to the idling unit.

14. In a boat drive, an idling unit, a propeller shaft having provision for operative connections adjacent both ends, clutch connections between the idling unit and both ends of the propeller shaft, and equalizing means whereby the respective clutch connections are at all times equally engaged.

15. In a boat drive, an idling unit, a propeller shaft, clutch connections between the idling unit and the respective ends of the

propeller shaft, means for maintaining the respective clutch connections at all times equally in engagement, and means for causing operation of the propeller shaft at a desired speed relative to the idling unit.

16. In a boat drive, an idling unit comprising a plurality of counterbalanced shafts, a stationary clutch member on each shaft, a movable clutch member on each shaft, propelling means connected with the movable clutch members, and means for at all times maintaining the respective clutch members equally engaged.

In testimony whereof I have hereunto set my hand.
